John A. Bonnahatt
ATTORNEY.

UNITED STATES PATENT OFFICE.

OLIVER S. PIRKEY, OF CLEVELAND, OHIO.

SIGNAL FOR AUTOMOBILES.

Application filed November 22, 1923. Serial No. 676,332.

To all whom it may concern:

Be it known that I, OLIVER S. PIRKEY, a citizen of the United States, residing at Cleveland, in the county of Cuyahoga and

5 State of Ohio, have invented certain new and useful Improvements in Signals for Automobiles, of which the following is a specification.

This invention relates to improvements in

10 signals for automobiles and the like vehicles having for an object to provide a combined direction indicator and stop signal which may be readily visible to drivers and others in front and in back of the vehicle.

15 Another object is to provide a signal of this character in which the lamps are so mounted as to be clearly visible at unusual distances in the day time as well as at night.

A further object is to provide a signal of 20 this character comprising four pairs or sets of lamps, each pair being arranged upon one side and at the front or rear of the vehicle.

A still further object is to provide a signal of this character so constructed that 25 placing of lamps and other parts may be accomplished from within the vehicle.

It is likewise an object to arrange pairs of signal lamps upon the inner face of the wind shield and provide a set of control switches 30 upon the usual instrument board in a position which will permit of convenient operation of the signal system.

Other objects will be in part obvious and in part pointed out hereinafter.

35 In order that the invention and its mode of operation may be readily understood by persons skilled in the art, I have in the accompanying illustrative drawings, and in the following detailed description based 40 thereon set out one possible embodiment of the same.

In these drawings:

Fig. 1 is a skeleton plan view showing the arrangement of the front signals upon the 45 wind shield and the rear signals upon the vertical end portion of the automobile top or body.

Fig. 2 is a detail top plan view of one of the lamp carrying brackets arranged upon 50 a wind shield.

Fig. 3 is an elevation of the interior of the wind shield and instrument board showing the signal lamps and switches arranged thereon.

55 Fig. 4 is a detail elevation of one of the brackets and the associated parts.

Fig. 5 is a sectional view taken substantially on the line 5—5 of Figure 4; and

Fig. 6 is a view illustrating the circuit of 60 each pair of lamps.

Having more particular reference to the drawings, throughout which similar characters of reference designate similar parts, this improved signal may be broadly stated 65 as comprising a set of brackets each carrying a pair of lamps and adapted to be mounted upon opposite sides and adjacent each end of a motor vehicle or the like. As illustrated, these lamps and their brackets together are arranged upon the inside of an 70 automobile body and are readily accessible for repairs or removal.

In Figure 1 of the accompanying drawings 75 there is illustrated the general outline of an automobile "A" having at its front end the usual wind shield "W" and at the rear end the vertical portion "R" of the ordinary top or sedan body. As stated, the wind shield and the said rear portion of the body each

mount two pairs of transversely spaced 80 lamps, each pair being mounted upon a bracket 8 which is provided with horizontally spaced openings 9 for the reception of a pair of open ended housings or tubular sleeves 10. Positive connection as between

85 the sleeves 10 and the bracket 8 may be accomplished in any ordinary or preferred manner. As clearly shown in Figure 5 of the accompanying drawings the outer end of each sleeve or housing 10 is provided with a 90

pair of diametrically oppositely disposed bayonet slots 11 adapted for the reception of lugs or finger pieces 12 carried by a substantially cup shaped cap member 13 which snugly fits within the said end of the housing. Centrally arranged and formed integrally with the base of this cap is a recessed

95 portion 14 which provides for wiring connection to the lamp 15 removably mounted in a socket 16, said socket being carried by a reflector 17. This structure of a housing and the removable lamp carriers and associated parts is common to all of the sleeves or housings and, as is obvious, provides a very

100 simple construction which is highly desirable in that it permits ready removal of said carriers for repairing or replacing broken parts.

105 As indicated in Figure 2, the bracket member 8 has one end 18 off-set and arranged parallel with the main body portion to provide for attachment to one of the vertical

uprights 19 at the opposite ends of the stationary portion included in the structure of the usual wind shield. It is to be understood, that if desired, I may employ any of 5 the well known clamps to form connection as between the brackets 8 and the uprights 19. In application of these brackets to the rear end portions of the vehicle, suitable 10 openings are formed in the rear portion "R" for alinement with the sleeve or housing openings and the brackets are riveted or otherwise fastened in proper relative position.

As illustrated in Figure 4, current 15 conducting wires are brought out of opposite ends of the T head 20 and are then carried into the recessed portion of the cap member 13, thus forming a portion of one 20 side of the circuit for one pair of lamps. A portion of the other side of the circuit of each pair of lamps is formed by the bracket 8 which carries the sleeves 10.

Due to the arrangement of the lamps 15 at the inner-most end of the tubular sleeves or 25 housings 10 the signal will be clearly visible at all times.

The arrangement of the wiring connections between the control switch "C" and

the wind shield carrying brackets is accomplished through positioning the wires in 30 back of the instrument board I and consequently there are no exposed wires to cause trouble or inconvenience to the driver. The brackets with the lamps are readily removable and are of such a relative size as to occupy a minimum amount of space. 35

Manifestly, the construction shown is capable of considerable modification and such modification as may fall within the scope of my claim, I consider within the 40 spirit of my invention.

I claim:

An automobile signal comprising an elongated flat bracket arm having an offset portion at one end, said bracket having a pair 45 of horizontally spaced transverse openings, elongated open ended sleeves having one end set into said transverse openings, a cup like cap member telescoping into the other end 50 of each sleeve, a reflector fixed to the inner end of each cup, an electric lamp fixed in each reflector, and means for separably connecting the cap members and sleeves.

In testimony whereof I affix my signature.

OLIVER S. PIRKEY.
